CLAIM

The ornamental design for a computer front bezel, as shown and described.

DESCRIPTION

FIG. 1 is a perspective view of a computer front bezel showing a first embodiment of our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; FIG. 7 is a bottom plan view thereof; FIG. 8 is a perspective view thereof mounted to a computer case;

FIG. 9 is a perspective view of a computer front bezel showing a second embodiment of our new design; FIG. 10 is a front elevational view thereof; FIG. 11 is a rear elevational view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a perspective view thereof mounted to a computer case.

The computer case is shown in broken lines in FIGS. 8 and 16 for illustrative purposes only and form no part of the claimed design.
